United States Patent Office.

WILLIAM W. LYMAN, OF WEST MERIDEN, CONNECTICUT, ASSIGNOR TO
THE MERIDEN BRITANNIA COMPANY, OF SAME PLACE.

Letters Patent No. 69,922, dated October 15, 1867.

IMPROVEMENTS IN THE MANUFACTURE OF TEA AND COFFEE-POTS.

The Schedule referred to in these Letters Patent and making part of the same.

TO ALL WHOM IT MAY CONCERN:

Be it known that I, WILLIAM W. LYMAN, of West Meriden, county of New Haven, and State of Connecticut, have invented certain new and useful improvements in the Manufacture of Tea and Coffee-Pots; and to enable others skilled in the art to make and use, I will proceed to describe the same by referring to the drawing, in which the same letters indicate like parts in each of the figures.

The nature of this improvement consists in locking a hard metal bottom, such as copper &c., to the body of a Britannia tea or coffee-pot.

The invention consists further in locking the edge of a hard metal bottom on to the lower edge of a Britannia body of a tea or coffee-pot.

The invention consists further in locking the lower edge of a Britannia body on to the edge of a hard metal bottom of a tea or coffee-pot. In the accompanying drawings—

Figures 1 and 2 are vertical section views of the bottom and base of a tea or coffee-pot.

a is the base, *a'* is the bottom. The base *a* is made of soft metal, commonly called Britannia. The bottom *a'* is made of hard metal, as copper, &c. In fig. 1, the lower edge of the base *a* is turned or locked over the edge of the bottom. In fig. 2, the outer edge of the bottom is turned or locked over the lower edge of the base.

The process by which this improvement is effected will be understood from the following: A block or chuck is fitted to a spindle, (as the spindle of a lathe). The lower part of the body of the pot is fitted thereto, and the bottom *a'* is placed in its proper position against the lower edge of the body, and held in that position by a back pressure or centre pressure. Thus the edge of the bottom, or the edge of the body is spun or turned down firmly, one upon the other, by the (spinning process) use of pressure of a proper tool, as a planisher or knurling-tool, or what are commonly called spinning-tools; or, in other words, one part is spun down upon the other by the spinning process, thus producing a perfect joint, giving thereto a finished symmetrical appearance.

A very important advantage is derived from this mode or process of uniting the body and bottom of a pot. There is less liability of melting the body in the process of soldering, the soldering can be prosecuted with greater rapidity, and with less liability of melting the Britannia body, and it is also believed that a good joint can be produced without soldering. They may therefore be united with or without solder. Thus a cheaper, better, and more desirable article is produced thereby.

I believe I have thus shown the nature, construction, or process by which this improvement is effected, so as to enable others skilled to practise the same.

What I claim, therefore, and desire to secure by Letters Patent, is—

Uniting a hard metal bottom with a soft metal or Britannia body of a tea or coffee-pot, substantially as described.

I claim a tea or coffee-pot, substantially as described.

WM. W. LYMAN. [L. S.]
